US00D825523S

(12) **United States Design Patent** (10) **Patent No.:** **US D825,523 S**
Adams et al. (45) **Date of Patent:** **** Aug. 14, 2018**

(54) **SET OF EARBUDS**

(71) Applicant: **IAM.PLUS, LLC**, Los Angeles, CA (US)

(72) Inventors: **William J. Adams**, Los Angeles, CA (US); **Chandra Rathakrishnan**, Singapore (SG); **Duncan Burns**, Santa Monica, CA (US); **Tom Arbisi**, Woodland Hills, CA (US); **Simon James**, Simi Valley, CA (US)

(73) Assignee: **IAM.PLUS, LLC**, Los Angeles, CA (US)

(**) Term: **15 Years**

(21) Appl. No.: **29/550,690**

(22) Filed: **Jan. 6, 2016**

(51) LOC (11) Cl. **14-01**

(52) U.S. Cl.

USPC **D14/205**

(58) **Field of Classification Search**

(57) **CLAIM**

The ornamental design for set of earbuds, as shown and described.

DESCRIPTION

FIG. 1 is a perspective view of an embodiment of a set of earbuds.

FIG. 2 is a front view of the embodiment of the set of earbuds depicted in FIG. 1.

FIG. 3 is a rear view of the embodiment of the set of earbuds depicted in FIG. 1.

FIG. 4 is a left-side view of an outer portion of the embodiment of the set of earbuds depicted in FIG. 1.

FIG. 5 is a left-side view of an inner portion of the embodiment of the set of earbuds depicted in FIG. 1.

FIG. 6 is a right-side view of an inner portion of the embodiment of the set of earbuds depicted in FIG. 1.

FIG. 7 is a right-side view of an outer portion of the embodiment of the set of earbuds depicted in FIG. 1.

FIG. 8 is a top view of the embodiment of the set of earbuds depicted in FIG. 1; and,

FIG. 9 is a bottom view of the embodiment of the set of earbuds depicted in FIG. 1.

Objects shown in broken lines are shown for environmental purposes only and form no part of the claimed design.
